UNITED STATES PATENT OFFICE.

WALLER CROW AND JOHN C. SCHAFER, OF PITTSBURGH, PENNSYLVANIA, ASSIGNEES
TO SCHAFER POIDOMETER COMPANY, OF PITTSBURGH, PENNSYLVANIA, A COR-
PORATION OF PENNSYLVANIA.

FUEL-FEEDING APPARATUS.

Application filed August 23, 1920. Serial No. 405,393.

This invention relates to power sub-division and delivery of material.

This invention has utility when incorporated in a stoker, or apparatus for handling 5 coal as for fuel, part thereof, as herein disclosed, being operable for facilitating combustion.

Referring to the drawings:

Fig. 1 is an elevation of an embodiment 10 of the invention in a stoker, for furnaces, with an electric motor drive, parts being broken away;

Fig. 2 is a plan view, with parts broken away, of the apparatus of Fig. 1;

15 Fig. 3 is an end view of the apparatus of Fig. 1 with the delivery conduit omitted;

Fig. 4 is a plan view, with parts broken away, of the delivery way of the apparatus;

20 Fig. 5 is a fragmentary view of the crusher;

Fig. 6 is a partial vertical section of the apparatus of Fig. 1, the motor being shown in elevation;

25 Fig. 7 is a view, partially in section, of the adjustable eccentric of the apparatus for effecting the hopper drive;

Fig. 8 is a section of the eccentric, on an enlarged scale on the line VIII—VIII,

Fig. 7;

30 Fig. 9 is a detail view showing the slip-page connection in the holding of the eccentric adjustment; and

Fig. 10 is a reduced scale fragmentary showing of an installation hereunder.

35 Mounted on the base or bracket 1 as the general platform or support is a motor 2 having shaft 3 carrying a sprocket wheel 4 from which extends a sprocket chain 5 to sprocket wheel 6 on counter-shaft 7. The 40 remote end of this shaft 7 carries a pinion 8 in mesh with a gear wheel 9 as a positive speed reduction drive for shaft 10. The remote end of this shaft 10 has mounted thereon a sleeve 11 carrying a recessed member 12 (Fig. 8), which is connected by bolts 13 to a face-plate 14. There is thus mounted about this eccentric housing 12 an eccentric strap 15 having bronze bearing 16 between said strap 15 and this eccentric housing 45 12, 14.

50 This eccentric strap 15 has a pair of arms 17 (Fig. 1) as a fork therefrom, each arm being connected to an arm 18 mounted on a shaft 19, the arms 18 being fixed to form

angle levers with upstanding arms 20. 55 These upstanding arms 20 carry a ratchet 21 pivotally connected therebetween and normally held by spring 22 in mesh with ratchet wheel 23 as a slow speed drive for pinion 24 in mesh with gear 25 on the shaft 26 through hopper 27 of the main housing or frame 28.

This intermittent or slow speed drive device or speed reduction mechanism from this shaft 10 effects a fuel supply to the apparatus, for on this shaft 26 is a conveyor shown of the screw type. This conveyor in the region below the hopper 27 has a small diameter portion 28' for the slower feeding of the fuel. This small diameter portion 28', being in connection with a larger diameter portion 29, disposed above housing 30, discharges material into crusher housing 31, as well as relieves the conveyor portion 28' for more free operation. In this housing 75 portion 31, on the shaft 10, is disposed a toothed crusher wheel 32, which in its rotation, will grind or draw the coal between this wheel and lugs 33 in the housing, thereby crushing or grinding the coal to a 80 uniform size in the delivery of such fuel as by way of chute 34 into the housing section 35 therebelow. Of course there may be some fines with this coal, but the crusher will break it down to not exceed a certain diameter for which the crusher is set or designed.

In this housing portion 35, mounted on the shaft 7, which is of greater speed of rotation than the shaft 10, is a series of concaved blades 36, which, in the direction of rotation, cup or concave into the descending fuel and thereby engage such fuel for throwing it tangentially. This high speed rotary fan propeller or ejector may provide for delivering with the fuel a fluid, as air, in addition to scattering the fuel. Besides this intake opening 34 for the fuel, there is disposed in the housing 35 an intake opening 37, the flow into which may be regulated by pivoted cover 38 so that there may be a pumping or drawing in of air and throwing of such air and fuel into narrowed portion 39 of the discharge way to which the housing 35 delivers.

Accelerating means with fluid may further be used in mechanically accelerating the fuel and serving as a fluid floor for supporting the fuel, as by steam or air jets 40 in the

housing 35, slightly downwardly directed along the floor of the way 39 supplemented in nozzle clearing action by an additional downwardly directed fuel dispersing jet 41 in the upper part of this housing portion 39. When steam is used, these fluid accelerators also may assist in the proper combustion of the fuel, while, of course, with air, the oxygen also will assist.

From this narrowed throat portion 39 there is a widening section or delivery portion 42 terminating in an upwardly flaring portion 43 having dispersing ribs 44 therein. This flaring terminus of this discharge way may be water cooled as by supply of water from pipe 45 into the chamber 46 for the control of the temperature and flow therefrom by way of pipe 47.

As herein disclosed there is but one speed reduction to the first or high speed shaft 7 which handles the fan or high speed ejector delivery of the rotary fan. There is another speed reduction to the shaft 10 which drives the crusher and still travels at a high rate of speed. So these two high speed shafts effect a handling of the fuel in the stoker, fuel handler, or fuel feeding apparatus.

The slow speed drive is on the shaft 26 through the hopper 27 and the provision herein is such that in this intermittent slow speed drive device for the hopper, in event any material should come into the machine that cannot be handled as to conveying or gets clogged in the housing, the machine will automatically stop without any damage to the apparatus. To this end the sleeve 11 on the shaft 10 to which it is connected, carries the eccentric housing 12, 14. Eccentrically on this sleeve 11 is a wrist pin 48. On this pin 48 is a compound member in the form of a sleeve having a bearing 49 (Fig. 9) for the plate 14. Just inward from this bearing is a toothed wheel 50 and therefrom is a tapered friction portion or frusto-conical section 51. This is within the housing formed by the eccentric members 12, 14. Mounted in the housing 12, 14, is a pin 52, having thereon a tooth wheel 53 in mesh with the wheel 50, and rotatable about the structure 49, 50, 51, in effecting an eccentric adjustment of this eccentric housing 12, 14, with respect to the eccentric wrist pin 48 disposed as a crank with respect to the sleeve portion 11 on the shaft 10. When the desired position of eccentricity or adjustment is determined for thereby regulating the fall of the dog 22 onto the ratchet wheel 23, there may be locking or frictional holding in this adjustment by means of pin 54 parallel to the pin 52. This pin 54 has threaded portion 53, in the housing 12, 14, on which threaded portion is mounted a frictional shoe 56. Accordingly in rotating this pin 54 the threaded portion 53 may squeeze or urge this shoe 56 into gripping relation with the tapered portion

51 of the structure 49, 50, 51. This structure 49, 50, 51, is fixed with the pin 48. There is now a locking or binding of the eccentric adjustment for in so adjusting there is effected a slippage connection between the 70 drive for the crusher and the drive for the conveyor.

In the handling of fuel with this apparatus it will take the ordinary run-of-mine material and delivering such through the fuel 75 feeder, such material may run from very coarse to fine and there may be grading determining just how coarse the coarser particles may be, but they may be kept down to a maximum by the action of the crusher apparatus. The upwardly extending portion of the delivery terminus of the way effects such a spreading of the fuel that in practice there is a large percentage of the fuel which is ignited on entrance. While it is not contended that there is complete combustion in entrance owing to the size of the fuel particles which are delivered, there is effected a complete ignition of the material while it is suspended, thereby expediting the combustion and effecting such distribution of heat throughout the entire furnace chamber that it renders the operation of this stoker very uniform and efficient for fuel burning especially in areas of a large extent away from such stokers.

In adjusting the throw of the eccentric by rotating the housing 12, 14, about the wrist pin 48, the degree of adjustment may be quickly determined by graduations 57 on the end of the sleeve portion 49 in adjustment as to an index 58 on the eccentric front plate housing 14. This adjustment of the slippable eccentric connection of the eccentric may vary the speed of travel of the conveyor and in the instance that the conveyor is clogged, the eccentric slips on its adjustment back to concentric position while allowing the crusher and ejector to run along, notwithstanding the hopper is 110 stopped, and the machine may be immediately given attention by throwing out the motor and correcting the difficulty without any damage to the apparatus.

Instead of merely circulating the cooling 115 medium in the chamber, plugs 59 may have jet openings 60 for the discharge of a vapor sheet of steam for slowing up combustion of the finer fuel particles as well as providing combustion supporting means of some 120 slight gas producer attributes. However, in furnace 61, bed 62 of the coarser fuel particles on grate 63, emits gas similarly to a true gas producer. The ignition of such gas is thus effective for an extended region 125 of flame propagation. This apparatus is thus effective for an extended region of flame propagation. As the combustion is thus spread out there is a reduced peak temperature with complete combustion 130

throughout an enlarged region of heat distribution. This heat of combustion is humidified by steam supply through the grates from the jets 64, from the stoker or ignition jets 40, 41, and even these may be supplemented as may be found desirable in practice for special operations by jets 65 in the furnace 61. When used for rotary kiln operations, an initial temperature of eighteen hundred degrees to twenty-six hundred degrees Fahrenheit may be maintained with the heat so thoroughly used as to have the spent gases leave the remote end at one hundred seventy-five feet away at a temperature of from four hundred fifty to five hundred fifty degrees Fahrenheit.

What is claimed and it is desired to secure by Letters Patent is—

1. A fuel feeder embodying a delivery way, rotary impeller means having its axis transverse of said way and effective for projecting material tangentially of the impeller means through said way at a high velocity, said means having a way delivery side and 25 and an idle return side, and an air inlet duct to the impeller means cooperating with the impeller means in the idle return side only.

of the impeller means as a suction release, and means supplementing the impelling the material in said way from said impeller 30 means including fluid jet means adjacent the impeller means directed along said way and effective for giving an increased speed to the fuel as thrown by the impeller means.

2. A fuel feeder embodying a delivery 35 way having a discharge, rotary impeller means having its axis transverse of said way and effective for projecting material tangentially of the impeller means through said way under speed as imparted by said impeller means and having a way delivery side and an idle return side, an air inlet duct to the impeller means as a suction release in the idle return side only of the impeller means, and additional inlet means for imparting additional speed to the traveling fuel in said way, said means being directed downwardly and forwardly into the material in said way for providing a draught of fluid impinging against the bottom of and along over said 50 way toward said discharge.

In witness whereof we affix our signatures.

WALLER CROW.

JOHN C. SCHAFFER.
